DETECTOR MECHANISM FOR CROWN CAP ASSEMBLING MACHINES

Roy Earling, Baltimore, Md., assignor to Crown Cork & Seal Company, Inc., Baltimore, Md., a corporation of New York

Application May 16, 1934, Serial No. 726,013

7 Claims. (Cl. 209—82)

The present invention relates to a detector mechanism particularly adapted for use with a crown cap assembling machine and designed to detect and eject defective caps.

5 The principal object of the invention is to provide a mechanism which will remove from a cap manufacturing machine any cap which is not of proper manufacture. More particularly, the invention involves the provision of means for 10 removing from a crown cap assembling machine any cap which is not provided with a liner.

In manufacturing crown caps, it is customary to feed metal shells and the cork or cork composition liners for the same into an assembling machine in such a manner that a liner will be placed in each metal shell. The feeding of the liners sometimes becomes impeded, with the result that metal shells pass through the machine without receiving liners and are discharged into the same receptacle or stack with properly formed caps, that is, caps comprising lined shells. Unlined caps are of course of no value to the bottler and it is therefore desirable to separate such caps from the properly assembled caps at a point 25 prior to the discharge of the caps from the machine.

By the present invention, means is provided to engage each cap passing through an assembling machine, and the engaging means is so 30 designed that if a cap, that is, a metal shell, contains no liner, it will be automatically ejected from the machine. On the other hand, the engaging means will in no way interfere with the passage through the machine of caps which are 35 provided with proper liners.

Another important object of the invention is to provide a mechanism which will detect and eject unlined caps, which mechanism comprises a minimum number of moving parts and is so 40 designed that it may be readily applied to a cap manufacturing machine.

Various arrangements for detecting and ejecting unlined cap shells have heretofore been provided but these previous mechanisms have included a relatively large number of moving parts and, in some instances, have necessitated the use of electrical contact making means operated by the passage of caps through the machine to detect defective caps.

50 In the present application, the detector mechanism of my invention is shown applied to a cap assembling machine of well known construction and which is embodied in the invention disclosed in the application of John D. Elder, Serial No. 55 714,167, filed March 5, 1934, Machine and method

of manufacturing spot caps. The machine with which the invention is illustrated includes means to assemble metal shells and cushion liners and apply an adhesive to each shell before the liner is inserted therein. The assembled shell and liner are subsequently delivered, by a transfer dial or conveyor, to a pressure dial through which they then move. During the movement of the shell and liner through the pressure dial, they are maintained under pressure for a sufficient 10 period of time to cause the liner to be firmly secured to the shell.

It will, of course, be understood that the detector mechanism of the present invention is applicable to crown cap manufacturing machines 15 of numerous other types and that the use of the ejecting mechanism is not limited to use in the manufacture of crown caps. In fact, as will be obvious from the following specification, the mechanism is readily applicable to machines for 20 making any type of lined container closure and can operate in conjunction with cap handling elements of numerous types. Furthermore, the present mechanism may be used to detect and 25 eject closures which are deficient in various respects, its use not being necessarily limited to the detection and ejection of crown caps lacking a liner.

Other objects and advantages of the invention will be apparent from the following drawings, in 30 which:

Figure 1 is a side elevation of a cap manufacturing machine having the mechanism of the present invention applied thereto.

Figure 2 is a plan view of a section of a cap manufacturing machine, showing a portion of a transfer dial for moving caps from the feeding mechanism to the pressure dial of the machine and the application of my detector mechanism to the transfer dial.

Figure 3 is a vertical sectional view taken on a line corresponding to the line 3—3 of Figure 2 and showing the detector mechanism of the present invention, the transfer dial and a portion of the pressure dial of a cap assembling machine, the central portion of the transfer dial being omitted.

Figure 4 is a vertical sectional view of a portion of the detector mechanism taken on line 4—4 of Figure 2.

Figure 5 is a vertical sectional view of the detector mechanism taken on the line 5—5 of Figure 2 and showing an engaging element of the detector mechanism in engagement with a cap containing a liner; and

50 55

Figure 6 is a side view of the detector mechanism, looking from the left in Figure 2, the casing of the mechanism and the transfer dial of the cap assembling machine being shown in 5 vertical section.

The cap assembling machine with which the present invention is illustrated may be briefly described as including a hopper 30 for metal shells, the shells being delivered from the hopper by 10 a chute 31 and positioned upon a transfer plate 32 with their skirts extending upwardly. The shells are moved from the transfer plate 32 by a removing means 33 which conducts the shells to a horizontally disposed step-by-step conveyor 15 34. During their movement upon the step-by-step conveyor, the shells pass beneath a device 35 which deposits adhesive in the shell and, upon a slight continued movement of the shell to the left, this adhesive is spread over the inner side of the 20 top of the inverted shell by a spreading means 36. The conveyor 34 next moves the shells past a mechanism 37 which positions a cushion liner of cork or cork composition in each shell, the liners being supplied from a tube 38 through 25 which they move by gravity.

Continued movement of the step-by-step conveyor 34 carries the shell and the liner therein to a rotating transfer dial or conveyor 40 as shown in Figure 2.

30 The transfer dial 40 has pockets 41 circumferentially spaced about its upper periphery and a shell and liner is intended to be positioned in each of these pockets by the conveyor 34. It may be stated that the transfer dial is provided for the 35 purpose of moving the caps to a pressure dial 42 which holds the assembled shells and liners under pressure for a sufficient period of time to permit the adhesive to substantially harden so that the two parts will be firmly secured together.

40 All of the mechanism which has been described above is well known and is disclosed and described in detail in the application of John D. Elder, referred to above.

45 The detector mechanism of my invention includes a base 45 which is secured upon the frame of the cap assembling machine adjacent the periphery of the transfer dial 40 as shown in Figures 2 and 3. A casing 45a fits upon the base 45 to enclose the moving parts of the mechanism. A 50 vertical post 46 is fixed centrally of the base 45 and a rotating member 47 including a hub portion 48 and a horizontal flange 49 is rotatably supported upon the post 46 by means of anti-friction bearings. The member 47 has a ring gear or pinion 50 secured to its lower face, which pinion is rotated 55 through a train 51 of idler gears driven from a ring gear or pinion 40a fixed to the lower portion of the rotating transfer dial 40.

50 The rotating member 47 includes a flat ring 52 fixed to the upper end of the hub 48. Ring 52 and the flange portion of the member 47 are provided with circumferentially spaced and vertically aligned apertures in which are positioned cap 55 engaging elements 53 which, as shown in Figure 3, are formed as plungers provided with depending pins 54 at their lower ends. The elements 53 are preferably rotatable in the apertures. The plungers or cap engaging elements 53 are provided with annular flanges 55 which normally bear 70 upon the upper side of the flange 49. A ring 56 rests upon each flange 55, these rings being of sufficient weight to tend the plungers or cap engaging elements to the lowered position shown at the left in Figure 3 and in Figure 6. It will be 75 understood that suitable means of any other

form may be provided to tend the plungers or cap engaging elements to the downward position shown.

Each cap engaging element 53 is provided with a tapered head 57 having its side walls inwardly 5 and downwardly inclined at a relatively sharp angle.

A disk 58 is fixed to the upper end of the stationary post 46 above the rotating member 47 and an arcuate cam plate 59 projects from the periphery of the disk 58, this cam plate extending from a point spaced from the periphery of the transfer dial 40, as shown in Figure 2, to a point immediately adjacent the periphery of the transfer dial. The plate 59 is held upon the disk 58 10 by means of machine screws 60 extending through arcuate slots extending longitudinally of the plate, the provision of the slots enabling the plate to be adjusted circumferentially of the disk 59. The outer arcuate edge of the plate 59 overhangs the 15 periphery of the disk 58 and the upper face of the projecting portion of the plate is upwardly bevelled at its outer edge 61 in a longitudinal direction. The upper face of the inner edge 62 of the plate 59 is downwardly bevelled. By this arrangement, the tapered heads 57 of the plungers or cap engaging elements moving about the disk 58 20 will ride upwardly along the bevelled surface 61, thence along the plate 59 and off the downwardly bevelled portion 62.

30 A second cam plate 63 is provided upon the disk 58 and extends from a point adjacent the periphery of the transfer dial 40 and outwardly therefrom about the disk. Cam plate 63 has a swinging movement upon a stud 64 which extends 35 through an aperture in the plate and into the disk 58. The plate 63 has a transverse slot 65 adjacent its inner end through which passes a stud or machine screw 66. The free end of a spring 67 secured to the disk 58 bears upon the inner 40 end of cam plate 63 to normally hold it in outward position as shown in Figure 2, the slot 65 permitting the plate 63 to swing inwardly with respect to the screw 66 and spring 67 in a manner 45 hereinafter described. The cam plate 63 also extends past the periphery of the flange 58 and is upwardly bevelled at 68 on its inner edge and downwardly bevelled at its outer edge 69. By this arrangement, the tapered heads of the plungers or cap engaging elements may ride upwardly upon 50 the bevelled edge 68 and along the plate 63, to move off the plate at the outer bevelled edge 69. A chute 70, shown in Figures 2 and 6, is fitted in the base 45 and has its upper end positioned beneath the periphery of the transfer dial 40 and 55 the path of movement of cap engaging elements leaving the dial.

It will be noted that disk 58 and plates 59 and 63, together serve as a cam plate to guide the vertical movements of the cap engaging elements 60 53.

Operation of the cap detector mechanism is as follows:

The rotation of the transfer dial 40 will cause the caps positioned in the pockets 41 of the dial 65 by the conveyor 37 to be moved opposite the cap detector mechanism. The gearing between the transfer dial and the rotary member 47 of the cap ejecting mechanism is so arranged that the cap engaging elements 53 will, in effect, intermesh 70 with the pockets 41 of the transfer dial. That is to say, one of the cap engaging elements will be aligned with each pocket of the transfer dial as the rotary member 47 and the transfer dial rotate with each other.

As a cap engaging element 53 of the detector mechanism moves about the stationary disk 58 in a counter-clockwise direction, its tapered head will engage the bevelled surface 61 of the cam plate 59, raising the entire engaging element. As shown in Figure 4, the engaging element will be raised a sufficient distance by the cam plate 59 to have the pin 54 at its lower end pass above the upwardly extending skirt of the inverted cap 10 which is seated in the pocket 41 of the transfer dial into which or above which the engaging element is then moving. The tapered head of the engaging element will then ride down the inclined surface 62 at the inner end of the cam plate 59 15 and off the end of the cam plate so that the pin 54 at the lower end of the engaging element will drop into the cap positioned in the aligned pocket 41. The weighted ring 56 provided on the engaging element will insure that the latter will drop 20 promptly after leaving the cam plate 59.

If the cap which is positioned in the pocket 41 of the transfer dial is complete, that is, if it comprises both a metal shell and a cushion liner, the engaging element 53 will naturally not drop 25 as far as if no liner is in the metal shell and the engaging element will be kept partially raised as shown in Figure 5 so that its flange 55 will not contact with the flange 49 on the rotating member. The continued rotation of the member 47 30 will move the tapered head 57 of the engaging element against the inclined inner edge 68 of the cam plate 63 as shown in Figure 5 and the upward inclination of the surface 68 will cause the tapered head to ride up and upon the cam 35 plate as shown at A in Figure 6, lifting the engaging element so that its pin 54 will be raised above the upper edge of the skirt of the cap as the engaging element and cap move in diverging paths with the rotating bodies which carry them. In 40 short, the presence in a pocket 41 of the transfer dial of a cap having a liner therein will cause the engaging element to be kept raised sufficiently far that its tapered head will ride upon the cam plate 63 and up and out of the cap.

In the event that no liner is positioned in a cap 45 which comes opposite the detector mechanism, the corresponding engaging element of the detector mechanism will drop a greater distance in the cap. Because of this, the continued rotation of the member 47 will cause the tapered head 57 of the engaging element to stay beneath the cam plate 63 as shown at B in Figure 6 and the pin 54 on the engaging element will pull the cap or 50 metal shell out of the pocket 41 of the transfer dial and will slide it around on the base 45 of the detector mechanism to the chute 70 down which the shell will slide. Shells received from 55 the chute may be again placed in the shell hopper of the assembly machine.

The cap engaging element 53 shown at position 60 C in Figure 6 is also beneath the cam plate 63, having engaged a cap which contained no liner and having fed the cap to the chute 70.

The present mechanism is also efficient for 65 moving from the assembling machine any caps having liners therein of insufficient thickness, since the engaging element 53 will drop a greater distance into such a cap and will therefore pass beneath the cam plate 63 instead of riding above it, causing the defective cap to be withdrawn from the assembling machine.

In some instances, the liner of the cap may be 70 of a thickness to cause the engaging element aligned therewith to be held at such a height that the upper edge of the tapered head 57 of an en-

gaging element 53 will be either exactly horizontally aligned with the lower edge of the inclined surface 68 of the cam plate 63 or raised just sufficiently far above the latter as to bring the two edges into almost abutting contact. With 5 the two edges opposed in this manner, the engaging element might become locked with respect to the cam plate 63 were it not for the fact that the cam plate 63 is mounted for inward swinging movement against the action of the spring 67. 10 However, since the cam plate may swing inwardly, any damage by reason of the abutting relationship of the engaging element and cam plate will be prevented and the continued movement of the engaging element along the cam plate will 15 cause it to ride upwardly upon the inclined surface 68 of the latter.

After moving off the cam plate 63, the engaging element 53 will remain in lowered position until it again comes in contact with the cam plate 59. 20

It will be appreciated from the above that the mechanism of the present invention will separate caps according to whether the caps are of a desired configuration, i. e., in the present instance, according to whether they contain liners and are 25 therefore of a predetermined depth.

It will be understood that the invention is not limited to the details of construction shown in the drawings and described in the specification and that the example of the use of the mechanism 30 which has been given does not include all of the uses of which the mechanism is capable; also, that the phraseology employed in the specification is for the purpose of description and not of limitation. 35

I claim:—

1. A mechanism for gauging caps upon a cap conveyor, comprising a rotatable member, cap engaging means movable in said member, means to position said engaging means on a cap, cam 40 means to move said engaging means out of engagement with a cap of a predetermined configuration, means to hold said engaging means in contact with a cap not of said predetermined configuration, said cam means being movable with 45 respect to said engaging means to prevent the latter from being held against movement by contact thereof with a cap of improper configuration.

2. A mechanism for gauging caps upon a cap conveyor, comprising a supporting means, cap 50 engaging means movable in said supporting means, means to position said engaging means in contact with a cap, a control member to move said engaging means out of engagement with a cap of a predetermined configuration, means to hold said engaging means in contact with a cap not of said predetermined configuration, said control member being movable with respect to said 55 engaging means to prevent the latter from being held against movement by contact thereof with a cap of improper configuration.

3. A mechanism for gauging caps upon a cap conveyor, comprising a rotatable member, cap engaging means vertically movable in said member, means to position said engaging means on a 65 cap, cam means to move said engaging means out of engagement with a cap of a predetermined configuration, means to hold said engaging means in contact with a cap not of said predetermined configuration, said cam means being 70 movable with respect to said engaging means to prevent the latter from being held against movement by contact thereof with a cap of improper configuration.

4. A mechanism for gauging caps upon a con- 75

veyor, comprising a cap engaging element, means to move said element into the path of normal movement of the caps, into engagement therewith and then retract said element from the path of movement of the caps, and means to remove said element from engagement with a cap of predetermined configuration as the element is retracted from the path of movement of the caps, and to retain said element in engagement with a 10 cap not of said predetermined configuration as it is retracted from the normal path of the caps.

5. A mechanism for gauging caps upon a conveyor, comprising a vertically movable cap engaging element, means to move said element into the path of normal movement of the caps, into engagement therewith and then retract said element from the path of movement of the caps, and means to remove said element from engagement with a cap of predetermined configuration 15 as the element is retracted from the path of movement of the caps, and to retain said element in engagement with a cap not of said predetermined configuration as it is retracted from the normal path of the caps.

20 6. A mechanism for gauging caps upon, which caps are supported upon a conveyor, comprising a rotary support having a portion thereof overlapping the conveyor, a cap engaging element

carried in said rotary support to move into and out of the path of movement of the caps on the conveyor, means to move said element into engagement with the caps on the conveyor, and means to remove said element from gripping engagement with a cap of predetermined configuration as the element moves away from said conveyor and to retain said element in engagement with a cap not of said predetermined configuration as it moves away from said conveyor to conduct the cap from the conveyor. 5

7. A mechanism for gauging caps, which caps are supported upon a conveyor, comprising a rotary support having a portion thereof overlapping the conveyor, a cap engaging element 15 carried in said rotary support to move into and out of the path of movement of the caps on the conveyor, means to move said element into engagement with the caps on the conveyor, and cam means to remove said element from gripping engagement with a cap of predetermined configuration as the element moves away from said conveyor, said element being weighted to be retained in engagement with a cap not of said predetermined configuration as it moves away. 20 from said conveyor to conduct the cap from the conveyor. 25

ROY EARLING.
